UNITED STATES PATENT OFFICE.

SAMUEL R. GARNER, OF CASSVILLE, WIS., ASSIGNOR TO HIMSELF, JOSEPH BOCK, AUGUSTUS HUNTEMER, AND OTTO REINKE, OF SAME PLACE.

MACHINE FOR DRESSING HOOPS.

SPECIFICATION forming part of Letters Patent No. 252,207, dated January 10, 1882.

Application filed October 4, 1881. (Model.)

To all whom it may concern:

Be it known that I, SAMUEL R. GARNER, of Cassville, in the county of Grant and State of Wisconsin, have invented certain new and useful Improvements in Machines for Dressing Hoops, of which the following is a specification.

My improvements relate to machines for dressing box-straps and barrel and tierce hoops split from poles; and the invention consists in certain novel features in the feeding mechanism, as hereinafter described and claimed.

Reference is to be had to the accompanying drawings, forming part of this specification, in which similar letters of reference indicate corresponding parts in all the figures.

In the drawings, Figure 1 is a side elevation of a hoop-machine containing my improvements, and Fig. 2 is a plan view of the machine.

A is the bed of the machine, supported on a suitable frame.

a is a shaft, sustained at the level of the bed by suitable bearings and provided with a pulley, b, for connection of power.

B is the cutter-head fixed on shaft a.

25 e is a short shaft boxed on the lower part of the frame, and carrying a pulley, d, from which a belt passes to a pulley on shaft a.

e is a vertical shaft operating the feed-rollers, as hereinafter described, and driven from shaft e by gear-wheels, as shown, or by any suitable connection. The feed is from one side of bed A parallel with shaft a.

The cutter-head is formed of a disk, a', having a cup-shaped flange, b', on which the cutters f are attached, with their cutting-edges projecting into slots g formed in the flange. There are three cutters f shown; but more or less may be used, as required, and they conform to the curved form of the head, and are set at an 35 inclination to the axis of the head, so as to act with a slanting and gradually-deepening cut.

On the bed A, next to the edge of head B, is fixed a plate, h, having a raised edge, curved to the form of the cutter-head, for supporting 45 the hoop in the required position.

The feeding mechanism is as follows: At the side of bed A is hung a bent lever, i, on which is a loose roller, k, grooved for engaging the edge of the hoop. The lever is fitted at its outer end

to receive a weight, and extends through a slotted guide-piece, l, fixed on the frame. On the bed A is a slide, m, arranged to move in a grooveway to and from the face of head B, and carrying a vertical gage-roller, n, of rubber or faced with rubber. A lever, o, pivoted on the bed and connected to slide m, extends in contact with lever i in such a manner that the weight tends to move slide m toward the cutters and press the roller n to the hoop passing through. Beyond the cutter-head are two vertically-placed fluted rollers, p p', one of which, p, is on the shaft e, before mentioned, while the other roller, p', is on a fixed arbor. The shaft e and the separate arbor are sustained at their upper ends by a bridge, q, and are connected 55 for simultaneous movement by pinions r. The bed A is slotted for shaft e to pass, and a spring, s, fixed beneath the bed and bearing on the shaft, serves to press the roller p toward the other and allow for variations in thickness of 60 the finished hoop. The backward movement of slide m is limited by a set-screw, t.

In operation the half-round hoop is entered on edge beneath roller k, and passes between the gage-roller n and cutter-head with the bark side next to the roller, and then between the two rollers p p', which draw the hoop forward. The weighted lever i presses the hoop downward, and by acting on lever o and roller n presses it up to the cutters, while the curved 75 plate h acts to retain the hoop edge up and properly presented to the cutters. The rubber face of roller n allows knots to pass without the effect of reducing the average thickness of the finished hoop. The cutters f act first by 80 their lower corners and edges to cut the heart of the wood and then finish to a uniform thickness. As soon as the last end of the hoop passes roller k the lever i, being unsustained, exerts its weight to press the gage-roller n inward and the hoop end to the cutters, with the effect to taper or bevel off the end of the hoop as required for the lap. The shape of cutters a and the slanting cut obtained thereby prevent the removal of the wood in slivers that 85 might choke the machine. At the same time the cut assists the feed, so that the feed-rollers are not required to press so tightly as to strip 90 95

the bark. The feed-rollers $p p'$ are set on a line diagonally of the feed for the purpose of overcoming the natural bend of the hoop toward the bark side. The angular position of the rollers tends to press the hoop toward the gage-roller, and also to take the bend out of the finished hoop, so that they can be readily bundled.

I am aware that a cutter-head made in disk form and having a flanged periphery is not broadly new, and I am also aware that an adjustable head-block has been arranged directly in front of and adjustable feed-rollers at the side of the cutter-head; but

What I claim, and desire to secure by Letters Patent, is—

1. In a hoop dressing machine, the combination, with the grooved frame A and the cutter-head B, of the slide m , the gage-roller n , the lever o , and the weighted lever i , substantially as and for the purpose set forth.

2. In a hoop-dressing machine, the combina-

tion, with the frame A and the cutter-head B, of the slide m , the gage-roller n , the lever o , the weighted lever i , and the set-screw t , substantially as and for the purpose set forth.

3. In a hoop-dressing machine, the combination, with the frame A and the cutter-head B, of the slide m , the roller n , the lever o , the weighted lever i , and the grooved pressure-roller k , mounted loosely on said weighted lever, substantially as and for the purpose set forth.

4. In a hoop-dressing machine, the combination, with the frame A, provided with the guide-plate h , and the cutter-head B, of the grooved pressure-roller k , the adjustable gage-roller n , and the adjustable fluted feed-rollers $p p'$, substantially as and for the purpose set forth.

SAMUEL RUSSEL GARNER.
